(57) **CLAIM**

The ornamental design for gold armor, as shown and described.

DESCRIPTION

The file of this patent contains at least one drawing/photograph executed in color. Copies of this patent with color drawings will be provided by the Office upon request and payment of the necessary fee.

FIG. 1 is a front view of gold armor showing our new design, shown in color;

FIG. 2 is an enlarged view thereof;

FIG. 3 is a front view thereof, shown in grayscale; and,

FIG. 4 is an enlarged view thereof.

The broken lines depicting the remainder of the gold armor and figure show features that form no part of the claimed design.
